UNITED STATES PATENT OFFICE.

WREATHA J. RULAND, OF LAWTON, OKLAHOMA.

DESIGN FOR A PIN.

53,752.

Specification for Design.

Patented Aug. 26, 1919.

Application filed February 28, 1918. Serial No. 219,701. Term of patent 14 years.

To all whom it may concern:

Be it known that I, WREATHA J. RULAND, a citizen of the United States, residing at Lawton, in the county of Comanche and State of Oklahoma, have invented a new, original, and ornamental Design for Pins, of which the following is a specification, reference being had to the accompanying drawing, forming part thereof.

The figure is a plan view of the pin, showing my new design.

I claim:

The ornamental design for a pin, as shown.
WREATHA J. RULAND.
